SHOE

Bernard W. Price, San Francisco, Calif.

Application July 5, 1949, Serial No. 3,694

Term of patent 7 years

(Cl. D7—7)

To all whom it may concern:

Be it known that I, Bernard W. Price, a citizen of the United States and a resident of the city and county of San Francisco, State of California, have invented a new, original, and ornamental Design for a Shoe, of which the following is a specification, reference being had to the accompanying drawing, forming part thereof.

I claim:

The ornamental design for a shoe, as shown.
BERNARD W. PRICE.
